BEVELED EDGE SHARPENER

Samuel C. Hood, New York, N. Y.

Application August 19, 1939, Serial No. 290,937

3 Claims. (Cl. 51—214)

This invention relates to blade sharpening devices, with especial reference to the blades of hand shears, scissors and the like, in which the thin cutting edges of the blades are beveled in opposite directions.

To sharpen such blades the abrading tool, whether a file, stick of carborundum, emery, whetstone, etc., must be operated at a proper oblique angle with reference to the inner, flat surface of the blade or the results will be far from satisfactory; if applied at too great an angle the cutting edge of the shear blade becomes dulled, on the other hand if the angle is too acute, the blade is worn away unnecessarily and its cutting edge weakened.

The correct bevel of such blades varies in accordance with the material to be cut and therefore the abrading element should be adjustable; furthermore, the cutting edge must be maintained straight throughout its entire length or its appearance and operation both suffer.

It is therefore an object of this invention to provide a blade sharpening device including a block of abrasive material and a combined holder and guide adjustable at any angle relative to the blade.

A further feature is in the provision of a blade sharpener easily operated by hand throughout the entire length of the blade, keeping the cutting edge straight and at such angle as is most suitable for the work to be performed.

Another purpose is to produce an essentially simple device, inexpensive to manufacture and readily used even by inexperienced persons.

These objects are accomplished by the novel and practical construction and arrangement of few and simple parts hereinafter described and illustrated in the accompanying drawing, constituting an essential component of this disclosure, and in which:

Figure 1 is a perspective view of a blade sharpener made in accordance with the invention, indicating its application.

Figure 2 is an end elevational view thereof.

Figure 3 is a front elevational view of the same.

Figure 4 is a transverse sectional view showing the guides in different angular positions relative to the abrading element.

Figure 5 is a plan view of the guide blank.

Referring in greater detail to the drawing, a sheet of metal is stamped to produce a single unitary blank 15, substantially rectangular in profile having an elongated rectangular opening 16 in its central portion from both sides of which

extend guide plates 17 shaped triangularly with their outer convergent edges convexly curved as shown.

At the ends of the opening 16 are narrow arms 18 connected at their inner ends by circular bosses 19 having central perforations 20.

The bosses 19 are bent at a right angle to the plane of the guide plates 17, into parallelism, by twisting the arms 18, bringing the perforations into alignment, centrally of and in the plane of the opening 16.

A block 22 of abradant material, of rectangular cross section, its width greater than the width of the opening 16, and its thickness considerably less, is formed with a central passage 23, the block 15 closely fitting between the arms 18 and bosses 19.

Passing through the opening 23 and perforations 20 is a bolt 25, one end having a head 26 and the other screw threaded to receive a thumb nut 27, which upon being tightened on the bolt 20 draws the bosses into clamping engagement with the ends of the block 22, holding it firmly in any desired angular position relative to the guide plates.

From the foregoing it will be seen that the arrangement is such as to present two portions of the block on each of its two main sides into position for operation, as indicated best in Figure 4.

In operation the block is adjusted at an angle relative to the guide in conformity with the bevel 30 of the blade to be sharpened and moved longitudinally over its full length under such pressure as may be required; the simplicity of construction and operation is plainly apparent.

Obviously a file may be substituted for the block 22, the arrangement being as described.

Although the foregoing is descriptive of the best known embodiment of the invention, it is to be understood that all such minor changes and modifications may be made as may come within the scope of the appended claims.

Having thus described the invention including the manner of its construction and application, what is claimed as new and sought to secure by Letters Patent, is:

1. A beveled blade sharpener comprising an abrasive element having opposed flat surfaces, a unitary holder in which said element is pivotally mounted, means integral with said holder to guide a blade presented against either side of said element, and means to clamp said element in an adjusted position.

2. A beveled blade sharpener comprising an abrasive element of rectangular cross section having opposed flat surfaces and a central pas-

sage extending longitudinally therethrough, a flat holder apertured to receive said element, blade guides integral with said holder, perforate bosses at the ends of said holder, and a bolt 5 passing through said bosses and abrasive element whereby the latter may be clamped.

3. A beveled blade sharpener comprising a holder composed of a single piece of flat sheet metal having an elongated rectangular opening 10 in its central portion, opposed wing-like guides

at the sides of the opening, bosses at the ends of the opening turned at right angles to said guide elements, a rectangular block of abrading material disposed in the mentioned opening, said block pivoted to swing therein and of such size as to prevent complete revolution, a bolt passing through said bosses and block, and means on said bolt to clamp the block when in adjustment. 5
